UNITED STATES PATENT OFFICE.

JAMES A. GRAY, OF MALONE, NEW YORK.

TRAIN-STOPPING APPARATUS.

1,117,034.

Specification of Letters Patent. Patented Nov. 10, 1914.

Application filed March 28, 1913. Serial No. 757,442.

To all whom it may concern:

Be it known that I, JAMES A. GRAY, a citizen of the United States residing at Malone, in the county of Franklin and State of New York, have invented new and useful Improvements in Train-Stopping Apparatus, of which the following is a specification.

This invention relates to improvements in train stopping apparatus and in the present 10 instance is directed to an automatic apparatus designed to be operated from the road signal.

In carrying out the present invention, it is my purpose to provide an automatic train 15 stopping apparatus whereby the throttle valve of the engine will be closed and the engineer's air brake valve moved to a position to effect an application of the brakes to the wheels from one of the axles of a car, said 20 movements of the throttle and air brake valves from the axle being dependent upon the position of the road signal.

It is also my purpose to provide an apparatus of the class described which may 25 be used in conjunction with any type of signal system without necessitating the alteration of such system and whereby the train will be automatically brought to a standstill in the event of the engineer, through 30 negligence or otherwise, failing to observe the danger signal.

Furthermore, I aim to provide a train 35 stopping apparatus which will be entirely automatic in operation and which will permit the throttle valve and the engineer's air brake valve to be manually operated in the normal or inactive position of the apparatus.

The invention has for a further object the 40 provision of an apparatus of the type set forth which will embrace the desired features of simplicity, efficiency and durability coupled with cheapness of cost in manufacture and installation and which may be readily applied to any character of locomotive.

45 With the above and other objects in view, the invention consists in the construction, combination and arrangement of parts hereinafter set forth in and falling within the scope of the claims.

50 In the accompanying drawings; Figure 1 is a view in side elevation, partly in section, of a locomotive equipped with the present invention. Fig. 2 is a vertical cross sectional view through the locomotive, showing the relative positions of the road signal

and train carried stopping apparatus. Fig. 3 is an enlarged longitudinal sectional view through a form of belt shifter. Fig. 4 is a cross sectional view through the same. Fig. 4¹ is a detail view of the trip. Fig. 5 is a 65 view in elevation of the boiler head within the engine cab showing a further modified form of my invention, and Fig. 6 is a side elevation of the drums and gear wheel illustrated in Fig. 7.

Referring now to the accompanying drawings in detail, a conventional form of locomotive is indicated at A, while the numerals 1 and 2 respectively designate the throttle 70 valve rod and air brake handle.

Suitably fastened to the boiler head within the engine cab is a bed plate 3 and journaled in alining bearings carried by such bed plate is a horizontal shaft 4 formed of axially alining sections 5 and 6. Surrounding 75 the confronting or meeting ends of the sections 5 and 6 of the shaft is a loose pulley 7, while keyed upon the respective sections of the shaft at opposite sides of the loose pulley are fast pulleys 8 and 9. In the present 80 instance, the free end of each section 5, 6 has suitably fastened thereto a gear wheel 10 and a drum 12. A second horizontal shaft 13 is journaled in alining bearings carried by the bed plate 3 and is disposed an appropriate distance above the shaft 4 and immediately below the throttle valve rod 1 and at right angles to the latter, a toothed pinion 14 being fixed to the shaft 13 and meshing with a rock bar 15 on the lower side of 85 the throttle valve rod 1, while pinions 16, 16 are keyed upon the shaft 13 at opposite sides of the pinion 14. One of these pinions 16 meshes directly with the teeth formed on the periphery of the gear 10 on the section 5 90 of the horizontal shaft 4, while the remaining pinion 16 is adapted to be driven from the gear 10 on the section 6 of the shaft 4 through the medium of an idler pinion 17. One end of the shaft 13 is preferably extended 95 as at 18 and has connected thereto an operating handle 19 whereby the shaft 13 may be rotated to move the throttle valve rod and so enable the throttle to be opened and closed manually according to the direction of movement of the shaft 13. In the present instance, the drum 12 connected to each gear 10 carries a pin 20 to which is securely fastened one end of a chain or other flexible element 21, the free ends of both 100 105 110

chains 21, 21 being secured to a soft metal ring 22 carried by the engineer's air brake valve handle 2.

In the present form of my invention, one of the axles of the locomotive has a pulley 23 fast thereon and over such pulley and the loose pulley 7 on the shaft 4 is trained an endless belt 24, such belt being capable of movement onto one or the other of the fast pulleys 8 and 9 on the respective sections of the shaft 4. Any suitable form of belt shifter may be employed for moving the belt from the loose pulley onto one or the other of the fast pulleys. In this instance, I employ two belt shifters 25, 25 which extend outwardly from opposite sides of the engine cab and each belt shifter is held against operation by means of a trip 27 pivoted upon an appropriate part of the cab 20 and adapted to be moved out of the path of the shifter rod upon contacting with a signal set to danger.

The semaphore signal standards are indicated at 28 and as usual these standards are arranged along the roadway and spaced apart the desired or approved distances, each standard having pivoted thereon a semaphore blade 29 capable of being moved to danger position, that is to a plane at right angles to the vertical, by some suitable mechanism. These signal blades may be either train controlled, that is to say, automatic, or manually operated.

From the foregoing description taken in connection with the accompanying drawings, the construction, mode of operation and manner of employing my invention will be readily apparent. Should the signal blades 29 be in clear position and a train equipped with my improved apparatus be proceeding along the right of way, it will be observed that the signal blades will be out of the path of movement of the respective trip 27 and the belt 24 and pulley 7 running idly with respect to the sections 5 and 6 of the shaft 4. By manipulating the operating handle 19, the engineer may control his throttle valve in accordance with prevailing conditions and the brake valve may be freely manipulated. However, should the semaphore blade in advance of said train be set to danger, the trip 27 at the right hand side of the cab will contact with the signal blade and so release the respective shifter rod 50 of the belt 24 so that the belt will be thrown from the loose pulley 7 onto the fast pulley 9 of the section 6. As the engine proceeds into the protected track area or danger zone, the section 6 of the shaft will be rotated 55 from the car axle through the medium of the pulley 23, belt 24 and fast pulley 9 thereby rotating the gear 10 and imparting movement to the pinion 17 and the respective pinion 16. Thus, the shaft 13 will be 60 moved to move the throttle valve rod 1 in-

wardly and so close the valve and shut off the flow of steam to the driving cylinders. Simultaneously with the closing of the throttle valve, the handle 2 of the brake valve is operated through the medium of 70 the respective chain 21, incident to such chain being wrapped about the periphery of the active gear 10 within the groove 20, to effect an emergency application of the 75 brake. On the other hand, should the locomotive be traversing the rails, rear end first, the trip 27 at the side thereof opposite from the first-mentioned trip will be disposed in the path of movement of the danger signal so that upon contacting with such signal 80 the respective belt shifter will be rendered operative to throw the belt from the loose pulley 7 onto the fast pulley 8 of the section 5, thereby throwing the throttle valve and operating the engineer's brake valve, through 85 the medium of the gear wheel 10 and the section 5 of the horizontal shaft 4, the pinion 16 and the pinion 15.

In Figs. 3 and 4, I have illustrated a preferred form of belt shifter. This belt shifter in the present instance, comprises a cylindrical casing 30 adapted to be secured to an appropriate part of the cab in a horizontal plane and having a restricted passage 31 formed therein adjacent to the outer end 95 thereof, while a disk 31' is suitably secured within the casing adjacent to the opposite end thereof. This disk is formed with an opening alining with the channel 31 and passed through such opening and slidably disposed within the casing is a plunger 32 having a reduced stem 33 disposed within the channel 31, a coiled expansion spring 34 encircling the plunger and abutting at one end against the adjacent face of the disk 31' and having its opposite end in engagement with a pin 36 carried by the plunger, the spring normally acting to force the reduced shank 33 of the plunger outwardly of the outer end of the casing. A trigger or trip 100 27 is pivoted upon the outer end of the casing 30 and normally lies in the path of movement of the shank 33 of the plunger so as to hold the latter against movement under the action of the spring, while to the 105 inner end of the plunger is connected one end of the shifter rod of the belt shifter, the opposite end of the latter being looped to encircle the belt. Thus, it will be seen that when the trigger or trip 27 is contacted by the signal, the plunger will be released so that the spring 35 may slide the latter within the casing and so shift the belt. Although I have shown and described one 110 particular form of belt shifter, it is to be 115 understood that I do not limit myself to the precise construction herein set forth.

In the modified construction illustrated in Figs. 5 and 6, a shaft 55' is journaled in suitable horizontally alining bearings 56

ried by a bed plate 56' bolted to the head of the boiler within the engine cab and upon such shaft is keyed a gear wheel 57' carrying upon one side a large drum 58' and a 5 relatively small drum 59, while also upon the shaft 55' is a loose pulley 60 and a fast pulley 61. Trained over the loose pulley and adapted to be thrown from the latter onto the fast pulley and vice versa, is a belt 10 62 adapted to be driven from a pulley on one of the axles of a locomotive or tender as the case may be. In this instance, the belt shifter lever 32 is connected through the medium of a wire or other suitable flexible element 15 63 with the respective tripping device. The gear wheel 57' meshes with a rack secured to the under side of the throttle valve rod, as in the preferred form of my invention, while a chain 64 or other flexible element 20 has one end connected to and is trained about the relatively large drum 58', such chain leading to and is connected with a valve located in the train line air pipe and adapted, when opened, to bring about in 25 effect, a service application of the brakes in contradistinction to an emergency application. A second chain 66 or other flexible element has one terminal thereof connected to the drum 59 and is wrapped thereabout 30 and has the free end thereof connected to the engineer's brake valve so as to effect an emergency application of the brakes to the wheels. Thus, it will be seen that under all circumstances, the brakes will be applied 35 in such manner as to reduce the wear and tear on the rolling stock incident to a sudden emergency application.

It will be seen that I have provided a train stopping apparatus which may be used in 40 conjunction with any type of signal system and wherein the throttle valve and the engineer's brake valve may be operated from one of the car axles, driving means being employed whereby the throttle valve and 45 brake valve may be operated as described, such means being dependent upon and operated from the road signal.

While I have herein shown and described certain preferred forms of my invention by 50 way of illustration, I wish it to be understood that I do not limit or confine myself to the precise details of construction herein described and delineated, as modification and variation may be made within the scope 55 of the claims and without departing from the spirit of the invention.

I claim:

1. In train stopping apparatus, the combination with a car axle and a throttle

valve, of a belt driven from said axle, a loose 60 pulley normally receiving said belt, a fast pulley, connections between said fast pulley and throttle valve whereby the latter may be closed, a belt shifter for shifting the belt from the loose to the fast pulley, a 65 casing, a plunger within said casing and capable of sliding movement therein and connected to said belt shifter, means acting upon said plunger to actuate the belt shifter to move the belt from the loose to the fast 70 pulley, a trigger disposed in the path of movement of said plunger and holding the same against movement under the action of the spring, and means for actuating said trigger to release said plunger. 75

2. In train stopping apparatus, the combination with a car axle and a throttle valve, of a belt driven from said axle, a loose pulley normally receiving said belt, a fast pulley, connections between said fast 80 pulley and throttle valve whereby the latter may be closed, a belt shifter for shifting the belt from the loose to the fast pulley, a casing, a plunger within said casing and capable of sliding movement therein 85 and connected to said belt shifter, means acting upon said plunger to actuate the belt shifter to move the belt from the loose to the fast pulley, a trigger disposed in the path of movement of said plunger and holding the same against movement under the action of the spring, and road signals adapted to actuate said trigger to release said plunger. 90

3. In train stopping apparatus, the combination with a car axle and a throttle valve, of a belt driven from said axle, a loose pulley normally receiving said belt, a fast pulley, connections between said fast pulley and throttle valve whereby the latter may be closed, a belt shifter for shifting the belt from the loose to the fast pulley, a casing, a plunger within said casing and capable of sliding movement therein 95 and connected to said belt shifter, a spring 100 acting upon said plunger to actuate the belt shifter to move the belt from the loose to the fast pulley, a trigger disposed in the path of movement of said plunger and holding the same against movement under the action of the spring, and means for actuating said trigger to release said plunger. 105

In testimony whereof I affix my signature in presence of two witnesses.

JAMES A. GRAY.
